(57) **CLAIM**

The ornamental design for a cigarette tube, as shown and described.

DESCRIPTION

1. Cigarette tube

1.1 : Perspective

1.2 : Front

Fig. 1.1 is a perspective view of a new design for a cigarette tube; fig. 1.2 is a front view thereof; the cigarette tube is intended to accommodate the tobacco blend and comprises a cylindrical mouthpiece made of carton, enclosed with a transparent sleeve made of rolling paper, which is longer than the mouthpiece.
